Application May 17, 1935, Serial No. 22,050
In Canada April 18, 1935

7 Claims. (Cl. 122—158)

This invention relates to improvements in furnaces and has, for its principal object, the provision of an efficient and economical furnace constructed mainly of standardized sheet metal sections capable of being welded or otherwise secured in assembled relation with a minimum amount of time and labor.

Other objects, advantages and characteristic features of the invention will be more readily understood from the following detailed description taken in connection with the accompanying drawings, in which—

Fig. 1 is a front view of a furnace constructed in accordance with this invention.

15 Fig. 2 is a rear view.

Fig. 3 is a top plan view.

Fig. 4 is a central vertical sectional view taken along the line 4—4 of Fig. 3.

Fig. 5 is a section along the line 5—5 of Fig. 4.

20 Fig. 6 is a front elevation of the grate assembly with certain of the grate sections removed.

Fig. 7 is a top plan view of the grate assembly with certain of the grate sections removed.

Fig. 8 is a top plan view of the grate shaking 25 spindle on which the grate sections are supported.

Fig. 9 is a bottom plan view of said spindle.

Fig. 10 is a top plan view of the main grate supporting bar.

30 Fig. 11 is a view similar to Fig. 4 but showing a modified type of furnace designed for use as an oil or gas burning furnace.

Fig. 12 is a plan view of a modified grate assembly, and

35 Fig. 13 is a vertical sectional view showing the grate assembly of Fig. 12 installed in a furnace.

The casing wall of the furnace appearing in Figs. 1 to 4 inclusive comprises two cylinders 5 and 6 spaced apart to define an intervening annular water space 7, each cylinder being formed by rolling a sheet of suitable gauge metal into cylindrical form and then welding the longitudinal edges of the sheet. A bottom ring 8 is welded to the lower ends of the cylinders 5 and 6 and serves to close off the lower end of the water space 7. Above the plate 8 the cylinders 5 and 6 are provided with suitable apertures in which are fitted the fire door 9, the ash pit door 10 and the ash pit damper structure 11. The upper end of cylinder 6 is welded to a top plate 12 provided with a central aperture 13 through which coal or other fuel is introduced into a fuel magazine 14 provided in the upper part of the furnace. The opening 13 is preferably bounded by an annular metal frame or rim 13a

affording a seat for a cover 15 which is hinged to the top plate 12 as indicated at 16.

The fuel magazine 14 is bounded by inner and outer sheet metal cones 17 and 18, the former having its upper edge welded to the upper edge 5 portion of the outer casing cylinder 6 and the latter having its upper edge welded to the upper edge of the inner casing cylinder 5. The cones 17 and 18 are spaced apart to define an intervening annular water space 19 closed at the bottom by a ring 19a welded to the lower ends of the cones. The upper portion of the water space 19 communicates with the upper portion of the water space 7 via an opening provided above the upper end of cylinder 5 which is shorter than cylinder 6. The lower portion of the water space 19 is also placed in communication with the water chamber 7 at a point intermediate the height of the latter. This is accomplished through the provision of a welded pipe 20 connecting an opening 21 in the lower portion of the cone 18 with an opening 22 in the casing cylinder 5.

A heat economizer comprising a casing 23, substantially U-shaped in horizontal cross section, 25 is welded to the casing cylinder 6 at the rear of the furnace. The rear and side walls of the casing 23 are formed by inner and outer sheet metal plates 24 and 25 defining an intervening water space 26 which communicates with the 30 water space 7 via suitable openings 27 provided in the casing cylinder 6 (see Fig. 5). The casing 23 is divided by a horizontal partition 28 into an upper compartment 29 and a lower compartment 30. The compartment 29 contains a hot water 35 service coil 31 and is in communication with the water chambers 7 and 19 through an opening 32 formed in the upper portion of the casing cylinder 6. Compartment 29 is also part of water space 26 and is provided with outlets 33, 34, and 40 35 through which the hot water circulating upwardly through the water chambers 7, 19, and 26 is delivered to the pipes and radiators of a hot water circulating system, the return pipes of which are connected to the lower portion of the 45 water chamber 19 at the inlets 36 and 37 provided for this purpose (see Figs. 3 and 5).

The compartment 30 of casing 23 is provided with a vertical baffle comprising an adjustable lower portion 40 and a movable upper damper 50 portion 41. The damper portion 41 is mounted on a horizontal pivot 42 so that it may be swung from the full to the dotted line position shown in Fig. 4. When the damper portion 41 is in the vertical position shown in Fig. 4 it co-operates 55

with the lower adjustable portion 40 to provide a tortuous passage 43 leading from the smoke outlet 44 of the furnace to a smoke outlet 45 provided at the upper rear portion of casing 23. When 5 the damper portion 41 of the baffle is moved to the horizontal position indicated by dotted lines in Fig. 4 the smoke or products of combustion escaping from the furnace outlet 44 are permitted to pass upwardly through the smoke outlet 45 of 10 the casing 23 without traversing the tortuous passage 43. As here shown, the lower baffle portion 40 is composed of two sections 40a and 40b held together by pin and slot connections 40c or other fastening means permitting adjustment to 15 vary the effective length or depth of the baffle.

The compartment 30 of casing 23 is closed at the bottom by a wall 46 provided with an opening 47 controlled by a draft damper 48 adapted to be operated in any suitable manner. In place of or 20 in addition to the heating coil 31 I may provide a heating coil 49 in the water chamber 17 of the fuel magazine 14.

The grate structure of the furnace is best shown in Figs. 6 to 10 inclusive. It comprises a 25 plurality of segment-shaped grate sections 50 assembled in conical formation. The upper end of each grate section is provided with a depending projection 51 fitted in one of the arms 52 of a cross-shaped slot formed in the head 53 of a 30 vertical spindle 54, which is journalled in the main grate supporting bar 55. As shown more clearly in Fig. 6, the head of the spindle 54 and the main supporting bar 55 are provided with intermeshing ratchet teeth 56 and 57 whereby the 35 spindle, together with the grate sections 50 are raised and lowered with an abrupt shock to shake the grate when the spindle and grate are rotated as hereinafter described. Below the main supporting bar 55 the spindle 54 is equipped with two 40 hub members 58 and 59 provided with intermeshing ratchet teeth 60 and 61. The hub 59 is fixed against turning movement on the spindle by means of a pin 62 or other fastening means. Hub 58 is loosely mounted on the spindle 54 so that it 45 is capable of independent turning and axial movement. This hub is also provided with a crank arm 63 having a slot 64 at its outer end through which extends an operating rod 65 slidably mounted in suitable bearings 66 and 66a, the 50 latter being formed in the bar 55. The operating rod 65 is provided with abutments 68 through the medium of which the crank arm 63 is operated to rotate the hub 58 in response to axial movement of the operating rod 65 which is provided with a 55 handle 65a at its front end. When the crank arm 63 is moved back and forth by the rod 65 the ratchet teeth 60 of the hub 58 co-operate with the ratchet teeth 61 of hub 59 to rotate the spindle and grate. Through co-operation of the 60 ratchet teeth 56 and 57 this rotation of spindle 54 and grate 50 results in an abrupt vertical shaking movement of the grate sections 50 as ratchet 59 slips over ratchet 57 and as the grate sections are rotated by ratchets 60 and 61. The 65 ends of the main grate supporting bar 55 are fitted in channel brackets 67 secured to opposite sides of the furnace casing. The bar 55 may be supported at different elevations in the channel brackets 67 by passing pins 69 through selected 70 openings 70 and 71 provided, respectively, in the channel brackets 67 and in the bar 55.

In Fig. 11 I have shown a modified type of furnace adapted to be used as an oil or gas burning furnace. In this case fuel magazine 14 is re- 75 placed by a hot water reservoir 73. This reserv-

oir is formed by an inverted sheet metal cone 74 having its upper end welded to the upper end of the casing cylinder 5 so that the upper part of the reservoir is in direct communication with a water space 7. The bottom of the reservoir is closed by 5 a welded plate 75 and is in communication with an intermediate portion of the water space 7 through the medium of a pipe 76 connecting an opening 77 in the cone 74 with an opening 78 in the casing cylinder 5. The top of the furnace 10 shown in Fig. 11 is closed off by a top plate 79 welded to the casing cylinder 6 and provided with outlets 80 through which hot water is delivered to the piping and radiators of a hot water circulating system, the return pipes of which are connected to the bottom of the water space 7 as 15 previously described in connection with Figs. 1 to 4 inclusive. The furnace shown in Fig. 11 is also provided with a heat economizer 23 that is substantially the same as that previously described. 20

A modified form of grate structure is shown in Figs. 12 and 13. In this case the conical grate comprises half sections 82 and 83 bolted together as indicated at 84. At predetermined points in its circumference each half section of the grate is 25 provided with vertical slots 86, 87, and 88, the upper end 87a of the slot 87 being positioned above the upper end 88a of the slot 88 but below the upper end 86a of the slot 86. The upper ends 86a, 87a, and 88a of the slots of each series thus 30 form vertical offset supporting surfaces adapted to be selectively engaged with one of a series of supporting lugs 89 to support the grate at different elevations. In Fig. 13 the grate is shown arranged with the lugs 89 received in the lower 35 slots 88 so that the grate is thus supported at its lowest level. If it is desired to lower the grate slightly this may be accomplished by changing the position of the grate so that the lugs 89 are received in the slots 87. To support the grate at 40 its lowest level, the lugs 89 are engaged in the slots 86. The grate may be raised and turned to bring the desired slots over the lugs 89 by means of a bar or other tool X inserted through the top 45 projections 90a of the grate. The lugs 89 are provided with base portions 90 welded or otherwise secured to the inner wall 5 of the furnace casing. These lugs are also provided with recesses 91 seating a removable ring 92 substantially bridging the gap between the furnace wall 5 and 50 the periphery of the grate structure.

Having thus described my invention, what I claim is:

1. A furnace comprising a casing formed by inner and outer sheet metal cylinders spaced 55 apart to define an intervening water space closed off at the lower ends of said cylinders, a fuel magazine in said casing bounded by spaced inner and outer conical shells of gradually decreasing circumference toward their lower ends, 60 said inner shell having its upper end abutting and directly secured to the upper end of the outer casing cylinder and said outer shell having its upper end likewise abutting and directly secured to the upper end of the inner casing 65 cylinder, the space between the lower ends of said shells being bridged by a closure ring and a single conduit connection between the lower portion of the space between said shells and an intermediate portion of the space between the 70 casing cylinders.

2. In a hot water furnace construction the combination of inner and outer sheet metal cylinders spaced apart to define an intervening water space closed off at the lower ends of the cylinders, 75

- said outer cylinder being of sufficient length to project above the upper end of the inner cylinder, spaced inner and outer conical shells, of gradually decreasing circumference towards their 5 lower ends, surrounded by the upper portions of said cylinders, the upper end of the inner shell being butted against and directly secured to the outer cylinder and the upper end of the outer shell being likewise butted against and directly 10 secured to the inner cylinder, said shells forming between them a supplementary water space closed off at the lower ends of the shell, the upper portion of said supplementary water space being in direct communication with the upper 15 portion of the water space between the cylinders and a pipe connection between the lower portion of the supplementary water space and an intermediate portion of the water space between said cylinders.
- 20 3. A furnace as set forth in claim 1 provided with an external vertical casing attached to the outer cylinder of the furnace, said vertical casing having double walls defining a supplementary water space in direct communication with the 25 water space of the furnace casing and means whereby products of combustion are passed from the furnace casing through the external casing to heat the water contained in said supplementary space.
- 30 4. A furnace as set forth in claim 1, provided with a gas outlet leading through the double walled casing, an external vertical casing attached to the outer cylinder of the furnace casing over the gas outlet to receive the gases therefrom, 35 said external casing having double walls defining a water space in direct communication with the water space of the furnace casing through openings in the outer cylinder of the furnace casing, said cylinder forming the inner wall of the external casing, and a gas outlet in the outer wall of said casing.
- 40 5. A furnace as set forth in claim 1, provided with a gas outlet leading through the double walled casing, an external vertical casing attached to the outer cylinder of the furnace casing 5 over the gas outlet to receive the gases therefrom, said external casing having double walls defining a water space which is directly connected through openings in the outer cylinder wall to all the previously mentioned water spaces, a gas outlet leading from the external 10 casing, and a gas outlet leading from the 15 external casing.
6. A furnace as set forth in claim 1, provided with a gas outlet leading through the double walled casing, an external vertical casing attached to the outer cylinder of the furnace casing 20 over the gas outlet to receive the gases therefrom, said external casing having double walls defining a water space in direct communication with the water space of the furnace casing through openings in the outer cylinder of the furnace casing, 25 said cylinder forming the inner wall of the external casing, a gas outlet leading from the external casing, and a partition arranged in said external casing to provide a tortuous gas passage between the gas outlets of the furnace and casing.
7. A furnace as set forth in claim 1 provided with a gas outlet leading through the double walled casing, an external vertical casing attached to the outer cylinder of the furnace casing 30 and mounted over the gas outlet to receive the gases therefrom, said external casing having double walls defining a water space which is directly connected through openings in the outer cylinder wall to all previously mentioned water spaces, a gas outlet leading from the external 35 casing and a vertically adjustable partition arranged in said external casing to provide a tortuous gas passage between the gas outlets of the furnace and casing.

JOHN F. FORMAN. 40
